UNITED STATES PATENT OFFICE.

EUGENE P. WOLF, OF CHICAGO, ILLINOIS.

SAFETY DELIVERY-RECEPTACLE.

1,155,778.

Specification of Letters Patent.

Patented Oct. 5, 1915.

Application filed November 14, 1914. Serial No. 872,067.

To all whom it may concern:

Be it known that I, EUGENE P. WOLF, a citizen of the United States, residing at Chicago, in the county of Cook and State 5 of Illinois, have invented certain new and useful Improvements in Safety Delivery-Receptacles, of which the following is a specification.

This invention relates to devices for insuring the safe receipt of articles delivered to the premises of purchasers at times when the premises may not be open for the immediate receipt and safe disposition of such articles within the premises.

It is a well known fact that in many places, particularly the large cities, there exists a great amount of petty thieving of such goods as milk and cream bottles, from the back porches of houses and flat buildings, that are commonly delivered at an early hour of the morning before the occupants of the premises are astir. Various devices for remedying this situation have been proposed; but, so far as I am aware, they 20 have for the most part proved too cumbersome and expensive to be practical and to command favorable attention from builders and property owners.

It is the prime object of the present invention to provide a simple, inexpensive and thoroughly practical and reliable, improved safety delivery receptacle for application to the back doors or walls of dwellings of all kinds, through the agency of which the delivery man can so dispose of the goods left by him as to prevent thieving and insure the safe receipt of the goods by the customer. To this end the invention consists in a safety delivery receptacle having the 40 novel features of construction and mode of use substantially as hereinafter described and more particularly pointed out in the claims.

In the accompanying drawing I have illustrated one practical and approved form in which my invention is embodied, and referring thereto, Figure 1 is a perspective elevational view of my improved safety delivery receptacle, showing the same in receiving 50 position. Fig. 2 is a horizontal section on the line 2—2 of Fig. 1. Fig. 3 is a horizontal section similar to Fig. 2, but showing the receptacle in delivery position. Fig. 4 is a vertical axial section through the upper por-

tion of the device, as seen on the line 4—4 55 of Fig. 1. Fig. 5 is a detail vertical section taken on the line 5—5 of Fig. 1, illustrating the construction and operation of the automatic locking device.

Referring to the drawing, 10 designates 60 the side wall, and 11 and 12 the flat top and bottom walls, respectively, of a substantially semicircular sheet-metal casing that is adapted to be fitted to and secured in a suitable opening in the panel of a door, or in a side 65 wall, Figs. 2 and 3 illustrating at 13 a horizontal section of what may be assumed to be the panel of a back door, suitable packing strips 14 being preferably employed to secure a snug joint between the casing and 70 its setting.

The casing is so mounted in the door that its open side 15 is on the outer side of the door; and the casing is further formed with an opening 16 in its side wall 10 that is 75 located on the inner side of the door. Centrally mounted within this casing, on independent vertically aligned pivots 17 and 18, is a circular sheet-metal holder comprising a cylindrical side wall or body portion 19 80 and flat top and bottom walls 20 and 21, respectively; the pivot bolts 17 and 18 connecting the top walls 11 and 20 and the bottom walls 12 and 21 of the casing and holder, respectively, thereby leaving within 85 the holder a single, entirely unobstructed receiving chamber having the full dimensions and capacity of the holder. The holder is also formed in its side or body wall 19 with a single opening 22 of substantially 90 the same form and area as the opening 16 of the casing.

The holder may be entered within the casing through the open side 15 of the latter, and has a loose sliding fit within the latter 95 so as to be capable of an easy turning movement on its pivots 17 and 18. From this it will be seen that the holder may readily be turned between the positions shown in Figs. 1 and 2, wherein it receives the goods from the delivery man, and the position shown in Fig. 3, wherein it delivers the goods to the occupant of the premises. In order that such a device may be thoroughly practicable for its chief intended purpose, it is essential 100 that the holder, after the goods have been placed therein and it has been turned to delivery position, should be locked in such 105

delivery position to prevent its being turned back to open or receiving position before the goods have been withdrawn. To accomplish this result I have provided the simple 5 automatic locking means illustrated in Figs. 1, 4 and 5, the same consisting of a locking bar 23 formed with an arm or shank 24 that is pivoted at 25 to the top wall 11 of the casing and normally lies within a locking 10 aperture 26 in said top wall 11, its lower end resting on the top wall 20 of the holder. Said top wall 20 is similarly provided with a locking aperture 27 so located that when the holder is turned to bring its opening 22 15 into register with the delivery opening 16 of the casing, the locking aperture 27 registers with the locking aperture 26, as shown in Fig. 5, and the locking bolt 23 automatically drops through said apertures and thereby 20 locks the holder against turning movement in either direction, the locking position of the bar 23 being shown by dotted lines in Fig. 5. The locking bar is preferably provided with a lug or tab 28 by which it may 25 be readily raised by a person on the inner side of the door to unlock the holder and permit it to be returned to receiving position.

To facilitate the turning of the holder 30 from the inside, the top wall 7 of the casing is formed with an arc-shaped slot 29, through which extends the stem or shank 30 of a knob 31, said stem or shank being secured in the top wall 20 of the holder. The 35 knob 31 not only provides a convenient handle for turning the holder from the inside, but, in co-operation with the slot 29, it forms a means for limiting the extent of turning movement of the holder, so that the latter 40 may be oscillated only between the receiving and delivery positions illustrated in Figs. 2 and 3. A similar operating knob or handle 32 is also mounted on the exposed portion of the top wall 20 of the holder for convenient 45 operation of the latter by the delivery man from the outside. Preferably, and as here shown, the inner opening 16 of the casing is guarded by a hinged door 33 held closed by a button or latch 34 to guard against the 50 entrance of cold air.

The operation of the device will be readily understood from the foregoing description. The delivery man places the milk, cream, groceries or other articles, within the 55 holder through the opening 22 of the latter, the parts being in the relative positions shown in Figs. 1 and 2. He then rotates the holder in the direction indicated by the arrow in Fig. 1 until the opening 22 registers with the opening 16 of the casing, at 60 which instant the locking bar 23 drops into locking position. In this position of the parts the goods are safely housed within the holder and inaccessible to thieves; and may 65 be removed by the purchaser of the goods

from within upon opening the door 33. When the goods have been removed, the locking bar 23 is raised and the holder turned back by the knob 31 to receiving position.

Practically all the parts of the device can be made from sheet-metal and formed and assembled at a very low cost, thus providing a device which will pay for itself in a very short time in its saving of goods which 70 would otherwise be stolen. While the described construction is preferred, it will be manifest that it may be modified in various minor details without substantially altering its character or lessening its practical utility; and hence the invention is not limited to all the details shown and described except to the extent defined in specific claims.

I claim:

1. In a safety delivery receptacle of the 85 character described, the combination of a substantially semicircular casing adapted to be set in a door with its open side on the outer side of the latter and formed with an inner side opening, a circular holder mounted in said casing on a vertical pivot and formed with a single receiving chamber and a single side opening adapted to register alternately with the openings of said casing, said holder being movable about its pivot 90 in both directions, and means for automatically locking said holder with its opening in register with the inner side opening of said casing.

2. In a safety delivery receptacle of the 100 character described, the combination of a substantially semicircular casing adapted to be set in a door with its open side on the outer side of the latter and formed with an inner side opening, a circular holder mounted in said casing on a vertical pivot and formed with a single receiving chamber and a single side opening adapted to register alternately with the openings of said casing, said holder being movable about its pivot in 105 both directions, means for automatically locking said holder with its opening in register with the inner side opening of said casing, and means for limiting the turning movement of said holder in both directions. 110

3. In a safety delivery receptacle of the character described, the combination of a substantially semicircular casing having top and bottom walls adapted to be set in a door with its open side on the outer side of the 120 door and formed with an inner side opening, a circular holder within said casing having top and bottom walls connected to the top and bottom walls of said casing by independent vertically aligned pivots and formed with a single unobstructed receiving chamber and a single side opening adapted to register alternately with the openings of said casing, said holder being movable about its pivot in both directions, and means for 125 130

automatically locking said holder with its opening in register with the inner side opening of said casing.

4. In a safety delivery receptacle of the character described, the combination of a substantially semicircular casing having top and bottom walls adapted to be set in a door with its open side on the outer side of the door and formed with an inner side opening, a circular holder within said casing having top and bottom walls connected to the top and bottom walls of said casing by independent vertically alined pivots and formed with a single unobstructed receiving chamber and a single side opening adapted to register alternately with the openings of said casing, said holder being movable about its pivot in both directions, means for turning said holder, means for automatically locking said holder with its opening in register with the inner side opening of said casing, and means for limiting the extent of turning movement of said holder in both directions.

25 5. In a safety delivery receptacle of the character described, the combination of a casing adapted to be set in a door and having two side openings on the outer and inner sides of the door, respectively, and a top wall formed with a locking aperture, a holder centrally mounted on a vertical pivot within said casing and having a top wall formed with a locking aperture and a side opening adapted to register alternately with the openings of said casing, and a locking bar mounted on the top wall of said casing and projecting through the aperture of the latter onto the top wall of said holder, said locking bar automatically engaging the locking aperture of said holder when the latter is turned to bring its opening into register with the inner opening of said casing.

6. In a safety delivery receptacle of the character described, the combination of a casing adapted to be set in a door and having two side openings on the outer and inner sides of the door, respectively, and a top wall formed with an arc-shaped slot, a holder centrally mounted on a vertical pivot within said casing and having a side opening adapted to register alternately with the openings of said casing, a knob having a shank extending through said slot and secured to said holder for turning the latter from the inner side of the door, and means for automatically locking said holder with its opening in register with the inner opening of said casing.

7. In a safety delivery receptacle of the character described, the combination of a substantially semicircular sheet-metal casing adapted to be set in a door with its open side on the outer side of the latter and formed with an inner side opening and with a top wall having an arc-shaped slot, a circular sheet-metal holder centrally mounted on a vertical pivot within said casing and having a top wall and a side opening adapted to register alternately with the openings of said casing, a knob having a shank extending through said slot and secured in the top wall of said holder for turning the latter from the inner side of the door, another knob mounted on the normally exposed portion of said holder for turning the latter from the outer side of the door, and means for automatically locking said holder with its opening in register with the inner opening of said casing.
